UNITED STATES PATENT OFFICE

2,478,940

APPARATUS FOR MAKING HOSE

Karl Pape, deceased, late of Dover, N. J., by Viola M. Pape, executrix, Dover, N. J., assignor to Resistoflex Corporation, Belleville, N. J., a corporation of New York

Original application January 26, 1946, Serial No. 643,732. Divided and this application March 19, 1947, Serial No. 735,818

7 Claims. (Cl. 154—6)

1

This invention relates to apparatus for use in manufacturing flexible hose, more particularly hose having two or more layers of textile fabric as components of its wall. More particularly it relates to apparatus adapted for use in forming an adhesive bond between any two of such layers according to the method described and claimed in the copending application of Karl Pape, Serial No. 643,732, filed January 26, 1946, of which this application is a division.

According to the method particularly described in the aforesaid parent application, a hose or flexible tubing having at least one layer of textile fabric on its outer surface, such as cotton braid for example, is first wetted with water and then coated with powdered polyvinyl alcohol in such an amount as will adhere to the wetted surface. A second layer of fabric is formed over the thus coated surface, for example by braiding, and the hose or tubing is then passed through a chamber in which it is bathed with steam.

While the apparatus herein described is adapted particularly to carrying out the aforesaid specific method, in which the adhesive is polyvinyl alcohol, the solvent therefor being water, it will readily be appreciated that it is equally adaptable for use with other types of comminuted adhesives used in dry form which may require the use of solvents other than water or the vapor thereof.

The present invention resides in the novel elements and combinations of elements hereinafter described, certain illustrative embodiments of which are shown in the drawings in which:

Fig. 1 is a diagrammatic representation of apparatus used in the making of hose having two or more layers of textile fabric adhered together; and

Fig. 2 is a vertical central section through that part of the apparatus in which the solvent and powdered adhesive material are applied to the hose, the latter being shown in position therein.

Referring to Fig. 1, the drawing shows certain parts of a common type of braiding machine, including a slotted plate 11, the slots in which determine the travel of carriers 12 which are actuated in the usual manner by a gear train (not shown). Each carrier holds the usual cylindrical cross-wound spool 15 and is provided with the usual yarn tensioning device 16. The plate 11 has a central aperture 18 through which passes the tubing 20 to be covered. As is well known, the carriers, which may vary in number but of which there are usually at least 24, travel about the tubing in such manner as to weave a braid

2

thereon at the point 21 where the yarns 22 meet the tubing. After being braided, the tubing passes over a capstan 24 against which it is pressed by a spring-actuated roller 25. Auxiliary rollers 26 may be used to assist in drawing the tubing through the braiding machine. As the tubing 20 leaves the capstan, it passes through a solvent applying device 28 comprising a chamber having an inlet 29 and an outlet 30 for the tubing, a pipe 31 for introducing solvent vapor into the chamber and another pipe 32 which serves as a drain. This device may be constructed as shown in U. S. Patents 2,262,514 and 2,262,515, issued November 11, 1941, to which reference is made for a more detailed description.

To maintain the tubing 20 under an inflating pressure during the processing, to provide a firm foundation for the braid and press the layers together, one end is connected at 34 with a compressed air line 35 by means of a flexible hose 36, the applied pressure being shown by a gage 38. It will be understood that the other end of the tubing will be closed to cause the desired air pressure to build up therein and that the tubing itself at this stage is impermeable to air by virtue of a non-porous layer.

The tubing entering the braiding machine is shown as having one layer of braid forming its outer surface and a second layer of braid as being applied on top of it. It will be understood, of course, that the process can be repeated as often as may be desired to provide any number of layers of braid.

Before the tubing 20 enters the braiding mechanism, it passes through a wetting and powder-applying device 40 shown in detail in Fig. 2. In passing through the lower part 41, the tubing is wetted with water or other solvent for the adhesive, supplied from a container 42 mounted for vertical movement as, for example, on the pivoted arm 44 so that by lowering the container 42 into the position shown in dotted lines, the liquid contained in the lower part 41 of the device 40 can be drained off in the event the movement of the tubing 20 is stopped for reasons hereinafter explained. In the upper part 45 of the device 40, the wetted tubing is coated with a layer of powdered adhesive, which naturally adheres to the moist fabric, and the next layer of braid is formed at the point 21, sealing the powder between the two layers of braid.

Referring to Fig. 2, the detailed construction of the device 40 is as follows: the lower part 41 comprises a cylindrical chamber internally threaded in its lower end to receive a bottom

member 50 having a flat lower surface 51 and a conical upper surface 52. The member 50 has a central aperture sufficient to permit the free passage of the tubing 20 therethrough and a watertight seal is provided by a soft rubber gasket 54 which may be compressed against the lower surface of member 50 by a threaded annular nut 55 bearing against a metal washer 56. A pipe 58 is screwed into an aperture in the chamber 41 which is positioned below the top of the member 50. A flexible hose 59 connects the pipe 58 with the container 42.

The solvent chamber 41 is externally threaded at its upper end to receive an internally threaded collar 60. This collar is also internally threaded at its upper end to receive a plug 61 forming the bottom of a hopper 62. The plug 61 has a central aperture 64 to permit free passage of tubing 20 and below this aperture is a second rubber washer 65, metal washer 66 and threaded annular collar 67, forming an adjustable seal to prevent the material in the hopper 62 from falling into the chamber 41 and which may be adjusted to remove excess solvent by exerting pressure on the tubing 20. In order to keep the loosely powdered material 70 in the hopper 62 in contact with the tubing 20 at all times, any suitable vibrating device 71 may be provided to be operated electrically or mechanically in a known manner so as to render the powder mobile and cause it to flow into contact with the tubing.

Operation

Tubing having one or more layers of braid on it is pushed up through washer 54, through the chamber 41 and through washer 65 and the hopper 62, chamber 41 being empty at this time. Nut 55 is adjusted with the minimum pressure required to keep liquid from leaking out of the chamber. Nut 67 may be adjusted to give any desired pressure on the tubing. The looser its adjustment the wetter the tubing will be as it enters the hopper. Reservoir 42 is raised to permit liquid to flow into chamber 41 to the desired depth. Because of the rather slow movement of tubing through a braider, it is sufficient if about an inch of water is maintained in chamber 41, the water level being adjusted by raising or lowering reservoir 42. Because it is necessary to stop braiders periodically to add yarn spools, chamber 41 should be drained by lowering the reservoir, especially where the hose liner is of polyvinyl alcohol composition, which is affected by water, to prevent excessive or non-uniform wetting of the braid or damage to the liner through the solvent action of excess water.

As tubing 20 passes upwardly through the device 40 and the braider, a layer of adhesive powder adheres to its moistened outer surface and a new layer of braid is applied thereover. When this composite article passes through the chamber 28, solvent vapor is supplied to the adhesive through the newly applied braid and this, together with the moisture in the underlying braid, exercise a dissolving action on the adhesive powder which becomes strongly adherent to both layers of braid. With the method described the adhesive, since it is not liquefied, does not soak into or impregnate either layer of braid and its adhesive action is therefore limited to the adjacent surface fibers of the two layers of braid, which is the only place where adhesive serves a useful purpose in bonding the layers. As a result, the braid layers maintain most of their original pliability. At the same time, because the concentration of adhesive

at the adhered surfaces is much greater than where a solution of adhesive is used, the strength of the bond between layers of braid is very much greater.

5 It is to be understood that the specific apparatus described above it to be construed merely as an illustrative embodiment of the invention which is defined in the appended claims and not as a limitation thereof since various changes in details of construction may be made without departing from the spirit of the invention as claimed.

What is claimed is:

1. Apparatus for adherently applying a second covering of textile fabric to a hose having a first covering of textile fabric comprising, in combination, means for wetting said first covering with solvent for an adhesive, means for applying a dry powdered adhesive to said wetted covering, means for forming said second covering over the powder-coated surface, and means for applying vapor to the hose externally of the second covering.

2. Apparatus for successively wetting and applying a dry comminuted material to a linear article passing therethrough in an upward direction comprising, a lower chamber, a seal at the bottom thereof adapted to permit the passage of said article, means for supplying liquid to said chamber, a hopper, a seal at the bottom thereof adapted to permit the passage of said article, said hopper being mounted above said chamber with said seals in alignment, whereby said article passes successively through said liquid and said material.

3. In combination with a braider adapted to weave braid on a tubing passing upwardly therethrough, said braid being formed at a braiding point, means for coating the surface of said tubing under said braid comprising, a hopper positioned beneath said braiding point adapted to contain dry comminuted material and having an opening in its bottom closely fitting said tubing, a liquid chamber positioned beneath said hopper and having an opening in its bottom closely fitting said tubing, a liquid reservoir, and a conduit connecting said chamber with said reservoir.

4. Apparatus for applying dry particulate material to the surface of a hose having an absorbent outer surface comprising, means for moving the hose upwardly, a pair of aligned receptacles mounted one above the other and having apertures through which said hose may pass, the lower one of said receptacles being adapted to contain fluid to wet the surface of said hose and the upper one of said receptacles being adapted to contain particulate material in contact with said wetted surface.

5. Apparatus according to claim 4 in which the receptacle for containing particulate material is equipped with agitating means to render said material mobile and maintain it in contact with said hose.

6. A coating device for linear articles comprising a hopper having a bottom opening, a compressible annular seal surrounding said opening, means for compressing said seal, a collar adapted for attachment to the lower part of said hopper, a liquid chamber having its upper end adapted for connection to said collar and having a bottom opening, a compressible annular seal around said opening, means for compressing said seal, and means for introducing liquid into and draining it from said chamber.

7. Apparatus for adherently applying a second

braid to a hose having a first braid thereon comprising, a solvent chamber through which the hose passes to wet the first braid, a hopper surrounding the path of the hose to contain a dry adhesive, a braider adapted to form braid over the adhesive-coated surface, a substantially closed chamber through which the hose passes after the formation of the second braid, and means for introducing vapor into said last mentioned chamber.

VIOLA M. PAPE,
Executrix of the Estate of Karl Pape, Deceased.
